MOLD BARROW

Leo O. Greeley, Cadillac, Mich., assignor to F. J. McCarthy, Inc., Cadillac, Mich., a corporation of Michigan

Application January 25, 1952, Serial No. 268,292

7 Claims. (Cl. 214—384)

This invention relates to conveyances and more particularly to a conveyance of the wheel barrow type particularly adapted to handle heavy, foundry molds.

Foundry molds, particularly sand molds, are normally very heavy articles due to their size and the weight of the sand forming the mold. After the mold has been poured, the handling of these molds is made even more difficult by the heat attendant the molten metal contained in the mold. In large foundries, the difficulty of transporting these molds is normally overcome by the use of suitable, mechanized, conveyor equipment. Such equipment, however, is not adapted to the needs of small foundries. Its size and the capital investment required are both too great to be practical. In small foundries it is necessary to move individually the molds from the mold making station to the point where they are poured and thereafter it is frequently necessary to move them to a shakeout unit where the completed casting and the sand are separated.

My invention is particularly adapted to the handling of these molds since it enables the operator to pick up and transport the mold using only the conveyance. Furthermore, the operator is not required to bring his hands or face adjacent a hot mold. The primary weight of the mold is carried by the wheel of the conveyance which also adapts the conveyance to movement of the mold over rough floor surfaces such as are frequently encountered in foundries. My invention is also adapted to meet the changing needs of small foundries since it may be quickly and easily adjusted to handle molds of various sizes and shapes.

These and other objects and purposes of my invention will be readily seen by those acquainted with the design and construction of foundry equipment upon reading the following specification and the accompanying drawings.

In the drawings:

Figure 1 is a plan view of my invention.

Figure 2 is a side, elevation view of my invention.

Figure 3 is an enlarged, detail of the lower end of the mold gripping, leg structure.

Figure 4 is a rear, elevation view of my invention showing only the rear portion of the invention's structure.

Figure 5 is an enlarged, fragmentary view of the latch mechanism on the leg structure, taken along the plane V—V of Figure 3.

In executing the objects and purposes of my invention, I have provided an open frame type structure designed to seat over a foundry mold with a wheel at one end for supporting the weight of the mold. Mounted on the frame and spaced from the wheel is a rear leg assembly adapted to support the rear end of the conveyance and to engage and support the other end of the mold. This leg structure is made adjustable with respect to the wheel to accommodate molds of different sizes. This leg structure includes a spring structure to cause the leg and finger to pivot away from the mold

2

whereby the mold may be released. Engagement and release of the mold may be effected entirely by the operator's foot.

In the following description the terms "forwardly" and "rearwardly" are frequently used and are to be taken to mean "forwardly" toward the wheel of the conveyance and "rearwardly" away therefrom.

Referring specifically to the drawings, the numeral 1 indicates a main frame including a pair of side members 2. The rearward portion of both side members is straight while the forward end portions of the side members 2 converge. The straight rearward portions of the side members 2 serve as a pair of handles for the conveyance. At their forward end the side members are bent down to form the vertical frame section 3. A rearwardly projecting, horizontal finger or plate 4 is rigidly secured to the lower end of the vertical frame section 3 by any suitable means such as welding. Substantially above the plate 4, the side members 2, where they constitute the vertical frame section 3, are joined by a cross brace 5. Projecting forwardly from the vertical frame section 3 are a pair of somewhat V-shaped brackets 6 having secured between them, at their forward ends, the wheel 7. The wheel 7 is preferably of the pneumatic type and is of such diameter that it will permit the conveyance to be readily moved over a rough surface with a heavy load. The wheel 7 supports the forward end of the conveyance above the floor sufficiently that the plate 4 clears the floor.

Extending between the straight portions of the side members 2 is the cross frame 10. The cross frame 10 consists of a cross bar 8 having on each end a long tubular collar 11. The tubular collars 11 are adapted to receive the side members 2 of the main frame therethrough whereby the cross frame 10 may slide forwardly and rearwardly along the main frame 1. The cross frame may be locked in any selected position by means of the set screws 12, one in each of the tubular collars 11.

The cross frame 10 mounts the rear leg assembly 40. The rear leg assembly includes a pair of rearwardly extending arms 13. Pivotedly mounted on the cross frame 10, one adjacent each of the arms 13, are a pair of legs 14. The legs 14 are somewhat L-shaped with a short section at their upper end extending almost horizontally and rearwardly from the cross frame 10. At their lower ends, the legs are joined by the finger or plate 15 which extends forwardly of the legs as a means for engaging the lower surface of a mold. The legs 14 are arranged parallel to each other and mount the H-shaped slide 16. The slide 16 consists of a cross member 17 having a tubular collar 18 on each end to seat around and slidably engage the legs 14. A pair of eyelets 19 are provided on the cross member 17 for anchoring the lower ends of the pair of spiral tension springs 20, anchored at their upper ends to the rearward end of the arms 13. The springs 20 are adapted to normally hold the slide 16 substantially above the plate 15 (Figure 4).

Mounted at the center of the cross member 17 is the latch assembly 21. The latch assembly includes an upper foot plate 22 rigidly secured to the cross member 17. Depending from the forward portion of the foot plate 22 are a pair of hangers 23, pivotally mounted between which is the latch arm 24. The latch arm 24 has a lower, hooked portion designed to engage the keeper or loop 25 on the plate 15. One portion of the latch arm 24 extends rearwardly and supports the lower foot plate 26. The lower foot plate 26 extends rearwardly substantially further than the upper foot plate 22. The foot plates 22 and 26 are joined by a bolt 27. The bolt 27 is provided with a clearance hole through the lower foot plate 26 and below the foot plate 26 is surrounded by

a spring 28 engaged at its lower end by a nut 29. The upper end of the spring 28 bears against the lower surface of the lower foot plate 26, urging the foot plate upwardly and the latch arm 24 into engagement with the keeper or loop 25.

The various parts of the frame structure of my invention are preferably fabricated from tubular material to reduce the weight of the conveyance.

Operation

To load the conveyance with a mold 30, the forward end of the conveyance is worked into position adjacent the mold until the plate 4 may be passed under the mold 30 with the mold centered about the longitudinal center line of the conveyance. During this positioning of the conveyance, the rear leg structure is retained in its rearward position as indicated by the broken lines in Figure 2. The rearward end of the conveyance is then swung into alignment with the mold. When the conveyance is in position, the operator by means of his foot, presses downwardly on the lower foot plate 26. This disengages the latch arm 24 from the keeper or loop 25. The tension of the springs 20 is then no longer effective to support the leg structure and it pivots by gravity until the plate 15 swings under the mold 30. The leg structure is induced to swing downwardly into this position by the rearward extension of the legs 14 adjacent the cross frame 10. Thus, the mold is cradled between the vertical frame section 3 and the rear leg assembly 40 and below the side members 2. The mold 30 is provided with supports 31 of sufficient height to permit the plates 4 and 15 to readily seat under the mold without first lifting the mold. By raising the handles, the plates 4 and 15 are caused to engage and lift the mold ready for transport. When the mold is to be released, the conveyance is lowered to disengage the plates 4 and 15. The operator, by means of his foot, then presses downwardly on the upper foot plate 22, extending the springs 20 and forcing the H-shaped slide 16 downwardly until the latch arm 24 engages the loop 25. By reason of the spring 28, the latch 24 will be forced to securely engage the loop 25. Upon release of the foot plate 22, the springs 20 will automatically pull the rear leg assembly upwardly into the position indicated in broken lines in Figure 2. The conveyance may now be readily wheeled away from the mold.

It will be seen that the operator is enabled to place the conveyance about the mold, load and unload the mold all without stooping to lift the mold or to bring the operator's hands or face adjacent the mold. This reduces fatigue by eliminating stooping. It also reduces danger of injury by making it possible for the operator to remain at a safe distance from a hot mold. At the same time, the mold is positively engaged while in transit by a structure which is inexpensive, light, and sturdy. The pivotal movement of the rear legs, in response to the springs 20, provides ample room whereby the operator may freely maneuver the conveyance when positioning it to load or unload a mold. A minimum of time is required for loading and unloading.

The frame of the conveyance is so designed that the side members 2 pass over the mold 30. This permits the mold to be, in effect, suspended from the frame. The weight of the mold is, therefore, maintained close to the floor at all times, producing great stability and making the loaded conveyance easy to balance by the operator. This same structural arrangement reduces the distance the operator has to lift the handles of the loaded conveyance to properly position them for easily handling.

Merely by loosening the set screws 12, the entire cross frame 10 may be moved toward or away from the wheel 7 thereby quickly adjusting the conveyance for transporting molds of various sizes and shapes.

I have described a preferred embodiment of my in-

vention. Various modifications of my invention may be made, each without departing from the principle thereof. Each of these modifications is to be considered as included in the hereinafter appended claims unless these 5 claims by their language expressly provide otherwise.

I claim:

1. In a conveyance of the wheel barrow type, the combination comprising: an L-shaped main frame including a forward, vertical portion and a rearward, horizontal portion, said rearward portion being joined to said forward portion at the upper end of said forward portion; means mounting a wheel to said forward portion; a rearwardly extending finger mounted to the lower end of said vertical portion of said main frame; a leg member having the same length as said forward portion of said main frame pivotally mounted to and between said rearward portion of said main frame for forward and rearward motion; said leg member extending downwardly from said main frame and means for locking said leg member in 10 said downwardly extending position perpendicular to said main frame; a forwardly extending finger mounted on the lower end of said leg member whereby an article may be cradled between said rearwardly extending finger and said forwardly extending finger with said fingers beneath said article.

2. In a conveyance as described in claim 1 wherein said means includes a latch slidably mounted on said leg member; a spring urging said latch upwardly; a keeper mounted to the lower end of said leg member and adapted 15 to be engaged by said latch.

3. In a conveyance as described in claim 1 wherein said means includes a latch slidably mounted on said leg member; a spring urging said latch upwardly; a keeper mounted to the lower end of said leg member and adapted 20 to be engaged by said latch; a first foot plate adapted to urge said latch downwardly; a second foot plate adapted to trip said latch.

4. In a conveyance of the wheel barrow type, the combination comprising: a main frame having a pair of spaced parallel handles at the rearward end and a supporting wheel at the forward end; said main frame being substantially L-shaped with one leg of said L extending rearwardly from adjacent said wheel to provide a pair of handles; said one leg being spaced substantially above said 25 wheel; a depending leg assembly pivotally mounted to said one leg of said frame; detachable spring means for urging said depending leg assembly upwardly and rearwardly; a first plate on the lower end of said main frame adjacent said wheel; a second plate on the lower end of said leg assembly; said plates being directed toward each other for suspending a load therebetween.

5. In a conveyance of the wheel barrow type, the combination including: a main body element including a forward, vertical portion and a rearward, horizontal portion, 30 each having a pair of spaced frame members; said rearward portion being joined to said forward portion at the upper end of said forward portion; means mounting a wheel to said forward portion; a rearwardly extending plate rigidly mounted to the lower end of said vertical portion of said main body element; a cross member slidably mounted to and between the frame members of the rearward portion of said main body element; means for locking said cross member against sliding movement; a pair of rearwardly projecting arms rigidly mounted on 35 said cross member; a pair of legs pivotally mounted on said cross member; a slide mounted on said legs for sliding movement therealong; a pair of springs, each of said springs at one end anchored to one of said arms and at the other end to said slide for urging said slide upwardly; a 40 latch mounted on said slide; a forwardly extending plate mounted on the lower end of said legs; a keeper mounted on said plate and adapted to engage said latch whereby the tension of said springs will urge said legs upwardly and rearwardly; a foot pedal on said latch whereby said 45 latch and said keeper may be disengaged.

6. In a conveyance of the wheel barrow type, the combination comprising: a main frame including a forward, vertical portion and a rearward, horizontal portion, said rearward portion being joined to said forward portion at the upper end of said forward portion; means mounting a wheel to said forward portion; a leg pivotally and slidably mounted on said rearward portion; locking means for holding said leg in a downwardly extending position perpendicular to said rearward portion of said frame; resilient means for pivoting said leg upwardly and rearwardly; said leg and said forward portion of said frame at their lower ends each having a finger for supporting an article therebetween.

7. In a conveyance of the wheel barrow type, the combination comprising: an inverted U-shaped frame having a forward leg and a rearward leg; a finger mounted on the bottom end of each leg of said frame, said fingers extending toward each other for supporting a load from beneath; a wheel mounted on said forward leg; said rearward leg being pivotally mounted to swing toward and

away from said forward leg and means to lock said rearward leg in a vertical position; means for urging said rearward leg upwardly and rearwardly upon release of said locking means; a portion of said frame extending 5 rearwardly from said rearward leg.
